BILLFOLD HAVING EXTERNAL ACCESS
MEANS

Herman E. Stock, New Haven, Conn.

Application January 31, 1945, Serial No. 575,377

2 Claims. (Cl. 150—38)

1

The present invention relates to improvements in billfolds, i. e., paper-money containers which fold to more conveniently fit the pockets of clothing or the like.

One of the objects of the present invention is to provide a superior billfold so constructed as to permit the contents to be readily observed.

Another object of the present invention is to provide a superior billfold which will securely hold bills but permit their ready removal from the billfold without requiring the opening of the latter.

A further object of the present invention is to provide a superior billfold which will expose a portion of the contents to view in such manner that the combination of the billfold itself and its contents compose an attractive ensemble.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a face view looking toward the inner face of one form of billfold embodying the present invention with the said billfold opened out;

Fig. 2 is an edge view thereof;

Fig. 3 is a rear face view of the billfold when the latter is folded;

Fig. 4 is a view similar to Fig. 3 but looking toward the front face thereof;

Fig. 5 is a view corresponding to Fig. 3 but additionally showing a bill installed in the billfold; and

Fig. 6 is a broken detail sectional view taken on the line 6—6 of Fig. 5, but on a larger scale.

The billfold herein chosen for purposes of illustrating a preferred form of the present invention may be formed of an oblong sheet 10 of leather or any other suitable material suitably proportioned to accommodate paper money. The said sheet 10 is formed about midway of its length with a transverse score or crease 11 to virtually divide the said sheet into a front-panel 12 and a complementary back-panel 13. The said panels may be folded with respect to each other about the score or crease 11, which latter serves as a hinge. At the outer end of the front-panel 12, the sheet 10 is also provided with a transverse score or crease 14 which virtually divides the said front-panel proper from a fastening-flap 15 and serves as a hinge between the latter and the said front-panel.

2

The fastening-flap 15 above referred to is provided centrally with a snap-fastener socket-member 16 having a socket 17 which is adapted to releasably receive a complementary stud 18 forming a part of a snap-fastener stud-member 19. The said stud-member 19 is mounted centrally in the back-panel 13 adjacent the outer edge thereof. The stud 18 is adapted to enter the socket 17 when the front-panel 12 and the back-panel 13 are folded together and the fastening-flap 15 is lapped over against the back face of the back-panel 13, as is especially well shown in Figs. 3 and 5.

On each of the respective opposite sides of the central score or crease 11, the sheet 10 is formed with one of two clearance-slots 20 and 21 which extend generally crosswise of the billfold from a point close to one edge thereof to a point close to the opposite edge of the billfold. The said clearance-slots serve to provide an integral intermediate tie-portion 22 between the respective inner-edges of the front-panel 12 proper and the back-panel 13 proper, as is especially well shown in Fig. 1. As thus located, the tie-portion 22 has the score or crease 11 extending centrally throughout its length.

Preferably and as shown, each of the clearance-slots 20 and 21 have their respective intermediate-portions symmetrically curved away from the score or crease 11, with the result that the tie-portion 22 is formed on each of its respective opposite edges with one of two oppositely-extending tab-portions 23 and 24.

Preferably, also, the front-panel 12 is formed with a sight-opening 25 so located as to enable the denominational numeral on a bill within the billfold, to be readily observed.

Bills may be inserted into the billfold above described in a variety of manners, but for purposes of convenience, let it be assumed that the billfold is opened out as illustrated in Figs. 1 and 2, so that the inner face thereof is uppermost. A bill or a group of bills may now be inserted from the inner face of the billfold through the clearance-slot 20, thence beneath the tie-portion 22 and through the clearance-slot 21 and onto the inner face of the billfold. The bill 26 may now be assumed to have reached the position illustrated by the dot-and-dash lines in Fig. 1.

With the bill 26 centrally positioned as indicated in Fig. 1, the front-panel 12 and the back-panel 13 may be folded toward each other about the hinge-point provided by the score or crease 11, and the fastening-flap 15 may be overlapped against the back face of the back-panel 13, to

cause the socket 17 in the socket-member 16 to snap-over the stud 18 of the stud-member 19 until the parts assume the positions in which they are illustrated in Figs. 3 to 6 inclusive.

When the bill 26 is installed in the billfold and the same is folded as above described, the fold-portion of the bill 26 will wrap itself around the exteriors of the tie-portion 22 and its oppositely-extending tab-portions 23 and 24, as is especially well shown in Fig. 6. As shown, the tab-portions 23 and 24 will be substantially pressed together by the wrapped-around portion of the bill 26, so that the portions of the respective inner-edges of the front-panel 12 and back-panel 13 from which the tab-portions 23 and 24 have been respectively displaced, will provide ample view of the bill 26 and will further provide finger-clearance notches 27 and 28.

Should it be desired, the thumb and forefinger may be entered into the finger-clearance notches 27 and 28 to clasp the folded portion of the bill 26, and to enable the said bill to be withdrawn from the billfold in the direction of the arrow 29 in Fig. 6, without requiring the opening-up of the billfold.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. As a new article of manufacture, a billfold, having external access-means, including in combination: a unitary structure providing a front-panel, a back-panel and a hinge-portion extending transversely of the billfold; the said front-panel and the said back-panel each being provided immediately adjacent the said hinge-portion with one of two complemental substantially-transverse clearance-slots through which may be extended the folded portion of a bill held between opposed inner faces of the said front-panel and the said back-panel when the said panels are folded together; both of the said clearance-slots extending closely adjacent to but terminating short of the respective opposite side-edges of the billfold and being laterally spaced apart in a direction lengthwise of the billfold by the said transverse hinge-portion which forms a tie between the opposite edges of the billfold at the point of junction of the said front-panel and the said back-panel, the said hinge-portion serving to support the inner face of the folded portion to support the inner face of the folded portion of a bill having its free ends extended respectively through the said clearance-slots into the interior of the billfold; each of the said transverse clearance-slots extending completely

through the panel in which it is formed from the inner to the outer surfaces thereof to enable a folded bill to be withdrawn from the interior of the billfold by gripping the exteriorly-exposed folded portion of the bill extending around the said hinge-portion.

2. As a new article of manufacture, a billfold, including in combination: a unitary structure providing a front-panel, a back-panel and a hinge-portion extending transversely of the billfold; the said front-panel and the said back-panel each being provided immediately adjacent the said hinge-portion with one of two complemental substantially-transverse clearance-slots through which may be extended the folded portion of a bill held between opposed inner faces of the said front-panel and the said back-panel when the said panels are folded together; both of the said clearance-slots extending closely adjacent to but terminating short of the respective opposite side-edges of the billfold and being laterally spaced apart in a direction lengthwise of the billfold by the said transverse hinge-portion which forms a tie between the opposite edges of the billfold at the point of junction of the said front-panel and the said back-panel, the said hinge-portion serving to support the inner face of the folded portion of a bill having its free ends extended respectively through the said clearance-slots into the interior of the billfold; each of the said transverse clearance-slots extending completely through the panel in which it is formed from the inner to the outer surfaces thereof to enable a folded bill to be withdrawn from the interior of the billfold by gripping the exteriorly-exposed folded portion of the bill extending around the said hinge-portion; each of the said clearance-slots having its central-portion curved away from the said hinge-portion to provide one of two complemental finger-clearance notches.
